UNITED STATES PATENT OFFICE.

VICTOR R. BROWNING AND EARL H. BROWNING, OF NOTTINGHAM, OHIO.

HOISTING MECHANISM.

No. 892,802.

Specification of Letters Patent.

Patented July 7, 1908.

Original application filed January 27, 1905, Serial No. 242,849. Divided and this application filed September 17, 1906.
Serial No. 334,936.

To all whom it may concern:

• Be it known that we, VICTOR R. BROWNING and EARL H. BROWNING, residing at Nottingham, in the county of Cuyahoga and State of Ohio, have invented a certain new and useful Improvement in Hoisting Mechanism, of which the following is a full, clear, and exact description, reference being had to the accompanying drawings.

10 Our invention relates to the hoisting mechanism of locomotive cranes and the like, and has for its general object the provision of means whereby the various parts of the hoisting mechanism may be conveniently assembled and disassembled and to the construction of parts whereby such assembling and disassembling is rendered possible.

The mechanism illustrated, described and claimed herein is a division of our application 20 242,849, filed Jan. 27th, 1905.

Generally stated, the invention may be defined as consisting of the combinations of elements embodied in the claims hereto annexed.

25 Figure 1 represents a sectional view taken through the housings just forward of the engine shaft, the lever brackets being shown in elevation and the operating levers being removed for clearness of illustration; Fig. 2 represents a similar section at right angles to the plane of Fig. 1, showing some of the operating levers; Figs. 3 and 4 represent respectively an end and a side elevation of one of the side housings; Fig. 5 represents an enlarged sectional view on the line 5—5 of Fig. 4; Fig. 6 represents a detail showing the manner in which access may be had to the shafting carried by the housings; Fig. 7 represents a front elevation of the boom hoisting drum.

1 represents the floor frame of a locomotive crane, said frame being provided with the depending integral hubs or sleeves 2 and 3, the former being provided for the reception of the journal 4 of the shaft 5, the lower end of which carries the pinion 6 by which the floor frame and the parts supported thereby may be rotated. The upper end of shaft 5 is provided with the bevel gear 7 meshing with the bevel pinion 8 on a horizontal shaft 9 which is driven from the main or engine shaft 10 through the bevel gears 11 and 12. The hub or sleeve 3 supports a journal 13 for a vertical shaft 14 by which the crane is driven along the track. The upper end of this shaft is provided with a

bevel gear 15 meshing with a bevel gear 16 on the counter-shaft 17. The shaft 17 is driven from the shaft 10 by means of the gears 18 and 19 on said shafts respectively and the clutch 20.

21 denotes a counter-shaft which is driven from the shaft 17 by means of gears 22 and 18 on said shafts respectively. (See Fig. 1.) Shaft 21 is provided with a bevel gear 23 and clutch 24, by means of which and the bevel gear 25 the motion of the shaft 21 may be transmitted to the vertical shaft 26. Shaft 26 is provided with a worm 27 engaging a worm gear 28 on shaft 29 which carries the drum 30 for hoisting and lowering the crane boom.

31 designates the hoisting drum mounted on a shaft 32 which is operated from the shaft 17 through the reduction gears 33 and 34 and clutch 35 (see Figs. 1 and 2).

The details of the means for driving and rotating the crane need no detailed description here, the same being shown, described and claimed in our application 242,849, 80 hereinbefore referred to.

Bolted to the floor proper of the frame 1, adjacent each edge of the same, are the housings 36. These housings support the engine shaft and most of the horizontal counter-shafts by which the various mechanisms of the crane are operated. Extending between these housings, near the upper front portions thereof, is the hollow frame or separator 37. This frame or separator is secured in place by bolts 38 (see Fig. 1). The engine shaft 10 and the counter-shaft 17 are supported in bearings 39, 40 formed in the lower portion of each of the housings. The front edge of each of the housings is inclined, as appears in Fig. 4, and in each inclined edge are formed a support 41 for the boom-hoist shaft 29 and a split bearing 41^a for the hoisting drum shaft 32. The horizontal counter-shaft 9 which operates the shaft 5, is supported by the pillow blocks 42 and is driven from the engine shaft 10 in the manner hereinbefore described.

The housings are particularly constructed with reference to the ease of assembling and 105 disassembling the shafting. Each of the said housings is provided near its lower edge with a recess 43 extending from the rear edge thereof to the vertical rib 44, from the upper portion of which the inclined rib 45 extends 110 which carries the bearings 41 and 41^a for the shafts 29 and 32. The strengthening rib 46

bounds the lower portion of the recess and is provided with the bearings 39 and 40 for the shafts 10 and 17 respectively. The bearings for these shafts are of the ordinary split type 5 and are provided with removable caps 47 and 48 respectively. A strengthening rib 44^a extends between rib 44 and bearing 41^a. The housing above the recess is provided with a rib 49 which merges at its rear end 10 with a sleeve 50. The corresponding lower rib 46 merges with the sleeve 51, both of said sleeves being in vertical alinement. A rearwardly and downwardly inclined rib 52 extends from the rear end of the rib 46 to the 15 base of the housing. A removable sleeve 53 having a corresponding inclined rib 54 is adapted to be inserted between the sleeves 50 and 51 to form therewith a continuous ribbed sleeve for the reception of a bolt 55. 20 This bolt is provided at its upper end with a screw-threaded portion 56 and near its lower end with a slot 57. A corresponding slot 58 is formed in the sleeve member 51 for the insertion of a key or locking-pin 59. This 25 key or locking-pin is provided with bottom lugs 60 and an intermediate recessed portion 61.

To assemble the shafts 10 and 17, they are inserted into the recesses 39, 40, respectively, 30 and are secured in place in their bearings, after which the sleeve member 53 is fitted between the members 50 and 51, the bolt 55 is inserted, the key or locking-pin 59 is inserted in place and, by means of a nut 62, 35 the bolt is tightened up and the sleeve members are locked together. When it is desired to disassemble the shafts 10 and 17, the nut 62 is slackened up, the locking-pin 59 removed, whereupon the sleeve member 53 may be 40 taken out and the said shafts may then be withdrawn through the recesses of the housings.

The hoisting-drum 31, with its shaft, may be readily removed by unscrewing the journal caps 63 and disconnecting the brake bands 64. This brake band being bolted at one end to the rod 65 extending through the frame or separator 37, it is only necessary to unscrew the nuts 66 from the upper end of 45 said rod to disconnect or slacken up the brake and permit the easy removal of the hoisting drum and its shaft.

The boom hoisting apparatus comprises the horizontal counter-shaft 21 journaled in 50 the lower end of brackets 67 integral with and depending from the frame or separator 37, the vertical worm shaft 26 driven from the shaft 21 and the worm 27 within the frame or separator 37, engaging the worm 55 gear 28 on the boom hoisting drum, the rear portion of which gear is within said casing or separator. The worm shaft is provided with bushings 68 and 69, the former being journaled in the bottom of the separator 37 and 60 the latter being journaled in a sleeve 70

which is removably fitted in an opening in the upper end of the said frame or separator. The lower end of the shaft 26, outside the frame or separator 37, is tapered, and the beveled gear 25 is removably secured to such 70 tapered portion by means of a nut 71. A pinch collar 72 surrounds the worm shaft, just above the worm, and is operated by means of the hand wheel 73 and shaft 74, to brake the worm shaft in a well known manner. The brackets 67 are in line with the brackets 75 when the latter are in place in the crane. 75

The worm gear is inclosed by means of an integral extension 76 of the frame or separator, the said frame and extension inclosing about half of the worm gear. The removable casing 77 completes the inclosure of said worm gear. On each side of the worm gear, outside of its casing, extends the drum 80 30 for the cable by which the boom is raised and lowered (see Fig. 7). The drum is provided with journals 78 within which are bushings 78^a. A shaft 29 rotatably supports the drum, said shaft being carried by 85 the bearings or supports 41, in which it is secured by a driving fit. The drum is removed by driving or forcing the shaft 29 on which the drum 30 is sleeved longitudinally 90 through the drum and through the ring bearings 41. After the shaft has been withdrawn, the drum may be lifted out or otherwise removed. 95

In order to remove the worm gear and its shaft, it is only necessary to remove the casing 77 and drive the shaft endwise through the drum in which it is journaled, whereupon the drum and worm gear may be withdrawn. To remove the worm and its 100 shaft, it is only necessary to unscrew the hand wheel 73 until the pinch collar is disengaged by the shaft 74, to unscrew the nut 71 and remove the bolts 79 securing the sleeve or journal 70 to the frame or separator 37, whereupon the worm and its shaft, together with the sleeve or journal 70, may be 105 lifted out of the casing or separator. 110

The end of the brake band 64 which is opposite the end connected with the brake rod is connected to the same sleeve 82 as hand lever 80 and foot lever 81, whereby said brake may be applied by hand or foot power or both (see Fig. 2). This sleeve is mounted in a shaft 83 supported between the lower end of one of the brackets 75 and the opposite 115 portion of the adjacent housing, the opening 84 being provided in said housing for this purpose. Where a double hoisting drum is employed, a similar shaft, brake and lever may be employed on the other side of the 120 machine, the brake-lever shaft being supported by the corresponding bracket and bearing on that side. In Fig. 1, an opening 84 is shown in the right hand housing for the 125 reception of such a shaft and a sleeve or bearing. 130

ing 85 is shown as provided for the reception of a brake rod similar to 65, but said shaft, operating levers and brake are omitted for clearness of illustration.

5 As will appear from Fig. 2, the hoisting drum shaft is supported out of line with and in front of the frame or separator 37. This gives an inclination to the brake rod 65. To accommodate this inclination, a long slot 86 is provided near each side of the front wall of said frame or separator and the upper surface of said frame or separator has cast therewith the integral bearings 85, said bearings having each an inclined bore to correspond 15 to the inclination of the rod 65 and the upper surface of each of said bearings being at right angles to the axis of the bore to provide suitable bearings for the adjusting nuts 66. The other end of the brake band, as 20 hereinbefore explained, is connected to the sleeve 82, which is mounted on the shaft or rod 83 in front of and below the frame or separator 37.

The brackets 75 are for the purpose of 25 supporting the shafts and quadrants of the various levers by which the brake and clutches are operated, but illustration and description of the clutch-operating levers are omitted from this application, the same 30 forming part of the subject matter of another application, also a division of application 242,849 filed Jan. 27, 1905. In Fig. 2, there is shown a quadrant 87 for the hand lever 80 which operates the brake band.

35 From the foregoing description, it will be apparent that the parts of the hoisting mechanism of our crane may be very readily, and conveniently assembled and disassembled,—a very important factor in the construction 40 of an effective and economical machine of this character.

1. The combination of a pair of shafts and a pair of housings for said shafts, each of said housings having a recess extending from the 45 side edge of the housing into the body thereof, the lower wall of each recess having a pair of bearings in which said shafts are removably journaled, substantially as specified.

2. The combination of a pair of shafts, a 50 pair of housings, each housing having a recess extending from an edge of the housing into the body thereof, the lower wall of each recess being provided with a pair of bearings for said shafts, and removable caps for said 55 bearings, substantially as specified.

3. In a crane or similar device, the combination of a side housing, said housing having a recess extending from one side edge of the housing into the body of the same, a bearing 60 in said recess, a shaft journaled in said bearing, sleeve members at the side edge in which the opening is formed, above and below said opening, a sleeve member adapted to be fitted into the opening between the first- 65 mentioned sleeve members, and means for

securing the same in place between the aforesaid sleeve members, substantially as specified.

4. The combination of a housing, said housing having a recess extending from an 70 edge of the housing into the body thereof, a bearing in said recess, a shaft journaled in said bearing, a sleeve member above and a sleeve member below the opening in the edge of the housing, a sleeve member adapted to 75 be inserted into said opening between the first mentioned sleeve members, a common bolt adapted to be inserted into all of said sleeve members, and means for locking said bolt in place to hold said sleeve members together, substantially as specified. 80

5. The combination of a pair of housings, each having a recess extending from an edge 85 of the housing into the body thereof, and alined sleeve members at such edge on opposite sides of said opening, a shaft journal in each of said recesses, a shaft in said journals, a sleeve member adapted to be inserted into the space between the alined sleeve members, and a locking bolt adapted to be fitted 90 into the three sleeve members of each housing to lock the removable sleeve member in place, substantially as specified.

6. In hoisting mechanism, the combination of a frame having opposed openings of 95 different sizes therein, a gear in said frame of smaller diameter than the larger opening, a shaft for said gear in said frame and having one end journaled in the smaller opening and projecting through the frame, a gear removably fitted to such end of the shaft, and a journal sleeve for the other end of the shaft 100 removably fitted in the larger opening, substantially as specified.

7. In hoisting mechanism, the combination of side housings, a hollow frame or separator extending between said housings, a shaft journaled in said housings adjacent said frame, a gear for operating said shaft, a gear removably journaled in said frame or 110 separator for operating the former gear, and means including a portion of said frame for inclosing said shaft gear, substantially as specified.

8. In hoisting mechanism, the combination of a shaft, a worm gear secured thereto, a hollow frame or casing partly surrounding said worm gear and its shaft, an extension for said frame inclosing the remainder of said worm gear and being removably secured to 115 said frame, a worm shaft removably journaled in said frame and having a worm thereon engaging said worm gear, a pinch collar on said worm shaft, an operating rod or shaft for said pinch collar removably engaging the 120 same, said worm gear and its shaft being removable through the frame, substantially as specified.

9. In hoisting apparatus, the combination of a frame having an opening therein, 130

- 2 a journal in said opening, a shaft in said frame having an end in said journal, a gear on said shaft within said frame, a pinch collar on said shaft, and an operating rod 5 removably threaded into said collar and extending through a wall of the frame, substantially as specified.
10. In hoisting mechanism, the combination of side housings having inclined edges, 10 a hollow frame connecting and spacing said housings adjacent said inclined edges, a driving gear in said frame, a driven gear, a shaft for said gear removably supported in the inclined edges of said housings, said 15 frame having an extension partly surrounding the driven gear, and a casing inclosing the remainder of said driven gear and removably secured to the frame extension, substantially as specified.
20. 11. The combination of a housing having a recess extending from one edge into the body thereof, a shaft bearing in said recess, a shaft removably journaled in said bearing, said housing being provided with aligned 25 sleeve members on opposite sides of the opening in the edge thereof, a sleeve member adapted to be inserted into the space between the first mentioned sleeve members, and means for securing all of said sleeve members 30 together, the removable sleeve member and one of the adjacent sleeve members being provided each with an inclined rib, substantially as specified.
12. In hoisting apparatus, the combination 35 of a pair of housings, one of said housings having a bearing therein, a frame extending between said housings, a bracket carried by said frame and having a bearing, a hoisting drum, a brake therefor, a shaft 40 supported in the aforesaid bearings, and means mounted on said shaft for operating said brake, substantially as specified.
13. In hoisting apparatus, the combination 45 of a pair of housings, a frame extending therebetween, a hoisting drum supported by said housings, a brake band for said drum, a brake rod connected to said band and adjustably supported by said frame, a shaft supported by said frame and a housing, an 50 operating lever rotatably mounted on said shaft, and a connection between said lever and said brake band, substantially as specified.
14. In hoisting apparatus, the combination 55 of a pair of housings, a frame extending therebetween, a hoisting drum supported by said housings, a brake band for said drum having one end adjustably supported by said frame, a shaft supported by said frame 60 and a housing, an operating lever rotatably mounted on said shaft, and a connection between said lever and the other end of said brake band, substantially as specified.
15. In hoisting apparatus, the combination 65 of a pair of side housings, a frame ex-
- tending between said housings intermediate the front and rear thereof, a hoisting drum supported by said housings on one side of said frame, a bracket supported from the other side of said frame, a bearing in said bracket and a bearing in one of said housings, a shaft supported in said bearings, a brake band for said drum having one end supported from said frame, a lever on said shaft, and a connection between said lever and the other end of said brake band, substantially as specified. 70
16. In hoisting apparatus, the combination of a drum, a shaft therefor, a pair of housings each having a bearing for said shaft, a frame extending between said housings, a brake band for the drum shaft, a rod extending through said frame and connected at one end to said band and having its other end detachably connected with said frame, 80 and means for operating said band from the other end thereof, substantially as specified. 85
17. In hoisting apparatus, the combination of a drum, a shaft therefor, a housing having a bearing for said shaft, a frame secured to said housing, a shaft supported by said frame and said housing, a brake-band for said drum having one end supported from said frame, a lever on the last mentioned shaft, and a connection between said 90 lever and the other end of said brake band, substantially as specified. 95
18. In hoisting apparatus, the combination of a drum, a shaft therefor, a pair of housings each provided with a bearing for said shaft, a frame extending across and secured to said housing, said frame having a bearing on one face thereof, a brake rod extending through said bearing, a brake band having one end connected to said rod, 100 operating means connected with the other end of said band, and means, as a nut, engaging the brake-rod bearing to permit adjustment of said rod, substantially as specified. 105
19. In hoisting apparatus, the combination 110 of a drum, a shaft therefor, a brake band for said shaft, and means for operating said band, said means comprising a shaft, a sleeve thereon, a connection between one end of said band and said sleeve, and a hand lever and a foot lever connected to said sleeve, substantially as specified. 115
20. In hoisting apparatus, the combination 120 of a drum, a shaft therefor, a brake band for said shaft, and means for operating said band, said means comprising a shaft, a hand lever and a foot lever mounted on said shaft, and a connection between one end of said band and said levers, substantially as specified. 125
21. In hoisting mechanism, the combination 130 of a pair of housings, a drum shaft supported by said housings adjacent the front thereof, a frame within said housings, above and to the rear of said drum, a brake band

for said drum having one end secured to said frame, a shaft mounted below and in front of said frame, a lever on said shaft, and a connection between the other end of said 5 brake band and said lever, substantially as specified.

22. In hoisting mechanism, the combination of a pair of housings, of a drum shaft supported by said housings adjacent the 10 front thereof, a frame within said housings, above and to the rear of said drum, said frame having its upper face provided with an inclined bearing, a brake band for said drum, a brake rod extending through said 15 bearing and having its lower end connected to one end of said band and provided with a nut at its upper end engaging said bearing, a brake-operating lever pivoted below and to to the rear of said frame, and a connection 20 between said lever and the other end of said brake band, substantially as specified.

23. In hoisting apparatus, the combination of a pair of housings, a frame extending between the upper portions of said housings, 25 a drum shaft extending between the lower portions of said housings and out of vertical alignment with said frame, a drum on said shaft, a brake band for said drum, said band having one end adjustably supported upon 30 the upper surface of said frame, and means connected with the other end of said band for operating the same, said means being located on the opposite side of said frame from the drum shaft.

35 24. In a crane or similar device, the combination of a housing having a recess extending from an edge into the body thereof, and aligned sleeve members at such edge, a shaft bearing in said recess, a sleeve member adapted to be inserted into the space between the 40 first mentioned sleeve members, a locking bolt adapted to be fitted into the three sleeve members of said housing and lock the removable sleeve member in place, and means 45 for securing the bolt in place, comprising a slot in the lower portion of the bolt, openings in opposite portions of said lower sleeve

member corresponding to said slot, and a key or locking pin extending through said openings and slot, the lower surface of the 50 key being provided with bottom lugs and with an intermediate recessed portion therebetween, the upper end of the bolt being provided with a thread and with a nut for said thread adapted to engage the upper sleeve 55 member, substantially as specified.

25. In a crane or similar device, the combination of a housing having a recess extending from one edge into the body thereof and aligned sleeve members at such edge, said recess having a bearing therein for a shaft, a sleeve member adapted to be inserted into the space between the aligned sleeve members, and means for locking the intermediate sleeve member in place, the intermediate and 65 the lower sleeve member of each housing being provided with an inclined rib, substantially as specified.

26. In a hoisting mechanism, the combination of a pair of side housings, a hollow 70 frame extending between said housings, a hoisting drum shaft supported by said housings adjacent to said frame, a gear on said shaft for operating the same, and a gear removably fitted in said frame for operating 75 the drum gear, substantially as specified.

27. In a hoisting apparatus, the combination of a drum and a shaft therefor, a pair of housings having each a bearing for said shaft, a frame extending between said housings, a shaft supported by said frame and one of said housings, a brake-band for said 80 drum having one end secured to said frame, and a lever on said shaft connected with the other end of said band.

In testimony whereof, we hereunto affix our signatures in the presence of two witnesses.

VICTOR R. BROWNING.
EARL H. BROWNING.
